UNITED STATES PATENT OFFICE

HARRY M. ROSS, OF INDIANAPOLIS, INDIANA, ASSIGNOR OF ONE-HALF TO BEVERIDGE PAPER COMPANY, OF INDIANAPOLIS, INDIANA, A CORPORATION

PROCESS OF DECORATING PAPER

Application filed August 3, 1928. Serial No. 297,233.

This invention relates to the process and means for decorating paper, and particularly that class of paper used for calendars, bris- 5 tols, cover paper, photo mounts, boxboard and the like, having an embossed and multi-colored surface or surfaces.

The object of the invention is to process the paper after embossing the same so as to brush a coloring material upon the high 10 surfaces thereof without effecting the coloring of the lower surfaces. This brings out in high relief the embossed design with two or more color effects applied to either one or both surfaces in a single operation.

Another object of the invention is to so process the paper as hereafter described, as to enable the work to be done in a rapid and economical manner for production purposes.

The full nature of the invention will be 20 more clearly understood from the accompanying drawings and the following description and claim:

Fig. 1 is a diagrammatic illustration of an apparatus for carrying out the process. Fig. 25 2 is a view taken on the line 2—2 of Fig. 1. Fig. 3 is an enlarged section through a strip of the embossed paper indicating the coloring effect upon one of the embossed surfaces thereof. Fig. 4 is a plan view of the decorated surface of the paper.

In the drawings there is illustrated a paper roll 10 which is suitably supported to carry a roll of relatively heavy smooth surfaced paper, which has a base color. The paper is 35 drawn from the roll 10 about the guide roll 11 over the counter roll 12 and caused to pass between said counter roll 12 and the embossing roll 13. The embossing roll is provided with a suitable embossing surface 14 adapted 40 to impress designs of varying character in the paper, leaving depressions and elevations in the surfaces thereof. The paper is then carried under the guide roll 15 and about the brushing rolls 16 to the carrying roll 17. Positioned to one side of the brushing rolls 16 45 and having axes slightly above the axes thereof, there are corresponding coloring rolls 18.

The rolls above referred to are all suitably supported and driven in the usual manner, 50 however, the brushing rolls 16 are caused to

rotate at a higher speed than the other rolls. A quantity of coloring material or paint 19 is carried between the respective brushing rolls 16 and coloring rolls 18, which rolls are in contact and caused to rotate in the direction indicated by the arrows. The coloring material or paint 19 is thus applied in a very thin coating, by reason of the close contact of the rolls 16 and 18 to the surfaces of the rolls 16, and carried thereby into contact with both 55 sides of the paper sheet 10.

By reason of the smooth even surfaces of the brushing rolls 16, they contact only with the elevations of the embossed paper. The film of coloring material carried on the surface of the brushing rolls is so thin that the coloring material likewise comes into contact only with the high spots or elevations formed in the paper. As the rolls 16 are caused to travel faster than the paper, the paint is 60 brushed therefrom onto the elevations by reason of their contact, but no paint or coloring material will be applied to the low spots or depressions.

The effect of the coloring thus obtained 65 may be varied, depending upon the speed at which the brushing rolls 16 are driven with respect to the speed at which the paper is drawn past the same. Wherein the speed is increased, the brushing effect will be lighter 70 and only the very highest spots or elevations of the paper will be brushed. Wherein the speed is reduced, approximating the speed of the paper, the paint will be applied to lower surfaces, although not entirely reaching the depressions. Thus, when the speed of the rolls 16 is decreased, but is still greater than the speed at which the paper is passed thereabout, there is more detail obtained in 75 the coloring effect.

As illustrated in Fig. 3, the paint 19 is shown applied to the high spots or elevations, whereas the depressions 20 are free therefrom so as to expose the natural or base color.

The diagrammatic illustration of the apparatus shows the stroke for applying the coloring to both sides of the paper during the same operation. In this connection, it will be apparent that different coloring may be applied 85 to opposite sides of the paper and different 90

shading effects obtained by varying the speed of the rolls 16 with respect to each other and the paper passing thereabout. It will also be understood that where desired, one of the 5 rolls 16, or its associated coloring roll 18, may be eliminated so as not to color one side of the paper and thereby apply the process to only one side thereof.

Whereas it has above been mentioned that 10 the rolls operated at a greater speed than the paper, the same effect and process may be employed wherein commercially practical, by operating the paper at a greater speed than the rolls. In other words, the effect is obtained by varying the relative speed between 15 the rolls and the paper.

The invention claimed is:

An apparatus for decorating paper including a pair of embossed rolls through which 20 the paper is continuously passed for embossing the surface thereof, a pair of coloring rolls mounted in said apparatus parallel with each other with their surfaces in rolling contact for providing a pocket adapted to receive 25 and retain therein a deposit of coloring material, means for continuously directing the paper from said embossing rolls about the outer free surface of one of said coloring rolls remote from the deposit of coloring material 30 and the adjacent roll and with the embossed surface in direct contact therewith, and means for imparting a different speed to said paper with respect to said coloring rolls, whereby it will receive a thin application of 35 coloring on the raised portion thereof leaving the depressed portion free therefrom.

In witness whereof, I have hereunto affixed my signature.

HARRY M. ROSS.
